FAUCET FIXTURE FOR A LAVATORY OR SIMILAR ARTICLE

Herbert V. Kohler, Kohler, Wis., assignor to Kohler Co.,
Kohler, Wis., a corporation of Wisconsin

Application January 9, 1959, Serial No. 54,103

Term of patent 14 years

(Cl. D91—3)

Fig. 1

Fig. 2

Fig. 3

Fig. 4

Fig. 1 is a perspective view of a faucet fixture for a lavatory or similar article, showing my new design;

Fig. 2 is a top plan view of the same;

Fig. 3 is a side elevational view thereof; and

Fig. 4 is a front elevational view of the faucet fixture. I claim:

The ornamental design for a faucet fixture for a lavatory or similar article, as shown.
